UNITED STATES PATENT OFFICE

CLARENCE HOLLIDAY AND CLAUDE H. NABER, OF HAMBURG, NEW YORK, ASSIGNEES
TO N & H SPREADERS, INC., OF HAMBURG, NEW YORK, A CORPORATION OF NEW
YORK

SPREADER

Application filed September 2, 1930. Serial No. 479,261.

This invention relates to an improved material spreader which is designed for, but not necessarily limited to, use in connection with a dumping truck wherein the spreader is adapted to receive material, such as crushed rock, which is dumped from the truck body and to spread such material over a prepared surface.

One object of the invention is a material spreader which may be easily secured to or detached from the body of the truck with which it is associated, the means by which such securing is effected being adaptable for co-operation with trucks of different size.

A further object is a spreader of the kind generally described which may be either secured to or removed from a truck by a single workman.

The invention is illustrated in the accompanying drawings in which:

Figure 1 is a side elevation of the spreader as attached to a truck, the latter being indicated in dotted lines.

Figure 2 is a side elevation of the same from the opposite side of the truck, the body of the latter being shown in dumping position.

Figure 3 is an end elevation of the same.

Figure 4 is a fragmentary view of the body of the spreader showing in detail the operating mechanism by which the spreader is raised and lowered during attaching, adjusting or removing operations.

Figure 5 is a fragmentary section of the support by which one end of the spreader is suspended from the cross bar of the truck and associated body parts, the section being taken along line 5-5 of Figure 1.

The spreader, as illustrated, may be employed in connection with a truck of any preferred type including a body B and a chassis C, the latter being provided with the usual cross bar K. It comprises a hopper H of any suitable construction, the construction shown consisting of vertical side walls 10 and 11 and downwardly converging front and rear walls 12 and 13 respectively, all of which are suitably secured together. A discharge opening 14 is formed in the wall 12 from which the material in the hopper H emerges as it

is being fed to the road. The thickness of the layer of material which is being spread is regulated by a door 15 which is secured to the wall 13 of the hopper and laterally co-extensive therewith. The door is held slidingly against the said wall by guide plates 16 which are secured to the wall and overlie the ends of the door. Movement of the door to vary the width of the discharge opening is effected by means of an operating lever 17 which extends along one side of the hopper and has its lower end secured to a shaft 18, the latter being journaled in brackets 19 secured to the wall 13 of the hopper. The shaft 18 carries arms 20, the outer ends of which are connected to links 21. The links 21 are pivotally connected at their other ends to an angle member 22 which is suitably secured to the door 15. Obviously, a movement of the operating lever 17 effects a movement of the arms 20 and the movement of the latter effects a corresponding movement of the door 15 through the links 21.

An agitator shaft 23 is arranged in the hopper H adjacent the discharge opening 14. The ends of the shaft project through the vertical side walls 10 and 11 of the hopper and are journaled in suitable bearings. The shaft 23 is driven by an auxiliary wheel 24 which frictionally engages the road. The wheel 24 is mounted in forks 25, the latter being loosely or pivotally mounted on a projecting end of the shaft 23. The wheel 24 carries a sprocket 26 which is connected by a chain 27 to a sprocket 28 fixed on the agitator shaft. Thus, upon movement of the truck the wheel 24 by virtue of its engagement with the road effects continuous rotation of the agitation shaft and this despite elevations and depressions in the road which may be encountered.

The wheel 24 does not support the hopper or its contents but supports only its own weight plus part of the weight of the forks in which it is mounted. The wheel, therefore, bears against the road with a relatively light force, which force is sufficient to drive the agitator shaft under normal operating conditions but insufficient to compel the continued rotation of the wheel when the said shaft is locked against rotation by the

wedging of material between the shaft and the walls of the hopper.

At the end adjacent the truck, the hopper H is suspended from the cross bar K by means of a pair of supporting members 29 which are formed with arms 29a which extend beneath the body of the truck to overlie and rest upon the cross bar. Each of the supporting members 29 is also formed with a vertical leg 29b to which the hopper is adjustably secured. To this end, two pairs of plates 30 are suitably secured, as by welding, to the wall 12 of the hopper. The plates, as illustrated, extend laterally from the said wall and at the edges opposite those by which they are secured to the hopper are formed to embrace the legs 29b of the supporting members. The plates are formed with a pair of openings 31 (Figs. 1 and 5) which register 20 with a series of similar openings 32 formed in the legs 29b. The hopper H may be secured in the position to which it is adjusted by means of pins 33 when the opening in the plates 30 have been registered with the desired pair of co-operating openings in the supporting members 29. U-bolts 34 may be employed in connection with the supporting members to prevent the supporting members from sliding from the cross bar K, the said 30 bolts co-operating with notches 35 in the arms 29a of the supporting members and being secured to brackets 36 which in turn are secured to the cross bar.

The end of the hopper remote from the truck is supported from the tail gate 37 of the truck by a cable 38 which passes over a pair of pulleys 39 suspended from the tail gate by hooks 40 and under a pair of pulleys 41 and 41a secured in relative staggered relation to an angle bar 42 of the hopper body. At one side of the hopper the cable 38 is secured to the angle bar 42 while at the other side it passes beneath the pulley 41a to the drum 43 of a windless 44 (Fig. 4) which is mounted between the side 11 and the front wall 12. The shaft 45 by which the drum is operated extends through the side wall 11 and carries at its outer end an operating handle 46. The drum carries at one end a ratchet wheel 47 which co-operates with a dog 48 mounted upon the side wall 11 to prevent unwinding of the cable from the drum when the hopper is supported above the road bed. At its opposite end the drum 55 is formed with an annular enlargement 49 which co-operates with a brake band 50. The band 50 may be contracted about the enlargement 49 by a lever 51 which is supported above the hopper by an arm 51a. Thus, when 60 the dog 48 is released to permit unwinding of the cable 38 with consequent downward movement of the hopper the lever 51 may be operated to set the brake band and thereby prevent downward movement of the hopper 65 at a speed sufficient to injure it.

The hopper H is provided with rocker bars 52, one of which is preferably secured to each side of the hopper. The said rocker bars support the hopper upon the road bed or other surface when it is not in use. They are 70 also availed of in arranging the spreader so that it may be readily attached to a truck.

It will be apparent from Figure 1 that upon removing the U-bolts 34, if such are used, the hopper may be lowered until it rests upon the road. During this downward movement of the hopper, the supporting members 29 are canted with the hopper away from the truck and while the arms 29a of the supporting members may remain resting 80 upon the cross bar K, their forward ends will be elevated above the said cross bar. When the hopper occupies this position, the truck may be disconnected therefrom simply by driving it forward, it being understood, 85 of course, that the pulleys 39 are first unhooked from the tail gate. In attaching the spreader to another truck, assuming that it remains in the position that it occupied when detached from the preceding truck in the 90 manner just described, the other truck is backed up toward the spreader. If it is similar to the preceding truck, that is to say to the extent that the cross bar of the chassis is substantially the same height from the 95 road bed, there will be no necessity of changing the original position of the spreader and the truck is backed toward the spreader until its cross bar passes beneath the forwardly and upwardly extending arms 29a of the 100 supporting members. If the cross bar of the following truck is at a different elevation than that of the preceding truck, the hopper may be rocked on the rocker bars 52 and the arms 29a may be positioned to co-operate 105 with the cross bar of the truck as it is backed toward the spreader.

In any event, after the arms 29a have been positioned over the cross bar of the truck, the pulleys 39 are hooked over the tail gate and the crank 46 of the windlass is operated to raise the hopper in the position shown in Figure 1. During the upward movement of the hopper, the arms 29a of the supporting members move toward and assume a horizontal position. The U-bolts 34 which may then be applied are ordinarily not necessary as the supporting members 29 under most conditions will, by virtue of the cable 38 and the hooked ends of the arms 29a, rest upon the cross bar in the manner desired. The said U-bolt, therefore, may or may not be utilized.

In dumping the material to be spread into the hopper of the spreader, the body 13 of the truck is tilted to the position shown in Figure 2, in which position the said material is fed by gravity into the hopper. During the raising of the body to this position, the hopper H would, unless otherwise prevented 125 130

be lowered toward the road bed. In order to avoid this, the windlass may be operated while the body of the truck is being raised to maintain the desired relative position between the hopper and the road bed. The truck may then proceed under its own power while feeding the material to be spread to the hopper H and the operating mechanism associated with the hopper insures a uniform distribution of the material over the prepared surface.

Due to the facility with which the spreader may be attached to and removed from the truck it may be employed in connection with a fleet of trucks. It has the further advantage that its securement or removal from a truck may be effected by a single workman and without the necessity of tools.

It will be apparent that while the invention is described and illustrated in connection with a truck having a dumping body, the latter is not essential and the spreader is equally applicable to other types of trucks.

Having fully described our invention, we claim:

1. In a spreader for attachment to a vehicle having a chassis and a body carried thereby, said chassis including an end cross bar above which the body is supported, the combination of a hopper, supporting members secured to said hopper and formed with rigid arms which extend away from the hopper and which are adapted to rest upon the said cross bar between the latter and the chassis of the vehicle, the said arms being movable by rocking said hopper to extend above said cross bar whereby the vehicle may be backed toward the hopper to position said cross bar beneath said arms and pulley and cable means connected to the body of said vehicle and co-operating with said supporting members for raising said hopper and for supporting it in the raised position.

2. In a spreader for attachment to a vehicle having a chassis and a body carried thereby, said chassis including an end bar above which said body is supported, the combination of a hopper, supporting members secured to said hopper and formed with rigid arms which extend away from the hopper and which are adapted to rest upon the cross bar between the latter and the chassis of the vehicle, the forward ends of said arms being movable by rocking said hopper to extend above said cross bar whereby the vehicle may be backed toward the hopper to position said cross bar beneath said arms, said supporting member being adjustable with respect to said hopper so that the hopper may be supported at the desired height, means for securing said members as adjusted and means connecting said hopper with the body of the vehicle for raising said hopper, said means co-operating with said supporting members as adjusted to support said hopper upon said vehicle.

3. In a spreader for attachment to a vehicle having a chassis and a body carried thereby, said chassis including an end bar above which said body is supported, the combination of a hopper, supporting members secured to said hopper and formed with rigid arms which extend away from the hopper and which are adapted to rest upon the cross bar between the latter and the chassis of the vehicle, the forward ends of said arms being movable by rocking said hopper to extend above said cross bar, whereby the vehicle may be backed toward the hopper to position said cross bar beneath the said arms, said supporting members being adjustable with respect to said hopper, means for securing said members as adjusted and pulley and cable means connecting said hopper with the body of said vehicle and co-operating with said supporting members as adjusted for raising said hopper and for supporting it in the position to which it is raised.

4. In a spreader for attachment to a vehicle having a chassis and a body carried thereby, said chassis including an end bar above which said body is supported, the combination of a hopper, supporting members secured to said hopper and formed with rigid arms which extend away from the hopper and which are adapted to rest upon the cross bar between the latter and the chassis of the vehicle, the said arms being movable by rocking said hopper to extend above said cross bar whereby the vehicle may be backed toward the hopper to position said cross bar beneath said arms, pulleys for removable attachment to the body of said vehicle, pulleys for connection to said hopper, a windlass carried by said hopper and a cable connecting all of said pulleys and the drum of said windlass, said windlass being available in conjunction with said supporting members for raising said hopper and for supporting it in the position to which it is raised.

5. In a spreader for attachment to a vehicle having a chassis and a body carried thereby, said chassis including an end cross bar above which said body is supported, the combination of a hopper, supporting members secured to said hopper and formed with rigid arms which extend away from the hopper and which are adapted to rest upon the cross bar between the latter and the chassis of the vehicle, the forward ends of said arms being movable by rocking said hopper to extend above said cross bar whereby the vehicle may be backed toward the hopper to position said cross bar beneath said arms, rocker bars carried by said hopper for facilitating the positioning of said arms and upon which said hopper may rest and means connecting said hopper to the body of said vehicle and co-operating with said supporting means for raising said hopper and for

supporting it in the position to which it is raised.

6. In a spreader attachment for a vehicle having a dumping type body, the combination of a hopper, an agitator shaft for distributing the material delivered to said hopper, a wheel operatively connected to said shaft and arranged to engage the surface over which the vehicle passes, thereby to drive the shaft upon movement of said vehicle, supporting members secured to said hopper and adapted for connection to the chassis of said vehicle and means connected to the body of said vehicle and co-operating with said supporting members for supporting the entire weight of said hopper and its contents when the said hopper is arranged to distribute material and the body of said vehicle is inclined so that the material may be delivered to said hopper by gravity.

7. In a spreader attachment for a vehicle having a dumping body, the combination of a hopper, an agitator shaft for distributing the material delivered to said hopper, a wheel operatively connected to said shaft and arranged to engage the surface over which the vehicle passes, thereby to drive the shaft upon movement of said vehicle, supporting members secured to said hopper and adapted for connection to the chassis of said vehicle and means connected to the body of said vehicle and cooperating with said supporting members for supporting the entire weight of said hopper and its contents when the hopper is arranged to distribute material and the body of said vehicle is inclined so that the material may be delivered to said hopper by gravity, said means being adjustable to adjust the position of said hopper to compensate for the angle of inclination of said body.

8. In a spreader attachment for a vehicle having a chassis and a body supported thereby, the combination of a hopper, supporting members secured to said hopper and adapted for connection to said chassis, arcuate elements secured to said hopper whereby the latter may be rocked to facilitate connection of the members to said chassis and means connected to the body of said vehicle and co-operating with said supporting members for supporting the entire weight of said hopper and its contents when the hopper is arranged to distribute material.

55. In testimony whereof we hereby affix our signatures.

CLARENCE HOLLIDAY.
